UNITED STATES PATENT OFFICE.

FRANZ KAHL, OF BERLIN, GERMANY, ASSIGNOR OF SIX-TENTHS TO WILLI LANDAU,
OF BERLIN, GERMANY.

THERAPEUTIC IMPLEMENT.

Application filed July 20, 1927, Serial No. 207,205, and in Germany November 24, 1926.

My invention relates to the treatment of mucous membranes of the nose, the purpose being to prevent and cure catarrhs, tumors, and the like.

5 In the drawings affixed to this specification and forming part thereof several forms of a device embodying my invention are illustrated diagrammatically by way of example.

10 In the drawings

Fig. 1 is an elevation illustrating a device for treating the mucous membranes of the nose.

15 Fig. 2 illustrates a similar device in which, however, the lamps used as heating and irradiating resistances are mounted on flexible spring supports.

20 Fig. 3 is a device serving the same purpose and which is held in position by a clamping action exerted on the portion of the nose separating the nostrils.

Fig. 4 shows a similar device adapted to be mounted on the bridge of the nose.

25 Referring first to Fig. 1, 1, 1 are two electric low voltage filament lamps, the bulbs of which may be made of blue glass and may be surrounded by gridlike apertured protective caps 2 of heat-insulating material. The lamps 1, 1 are mounted in sockets 3, which 30 are fixed to links 4 pivotally connected at 8 with intermediate links 5 turning about a common pivot 9 at the end of the hollow handle 6. The current supply leads 7 extend through this handle and their free ends 35 are connected to a pocket battery 40.

If the lamp bulbs consist of blue glass which is known to allow the passage of ultraviolet rays to a greater extent than ordinary glass, the mucous membranes of the 40 nose, besides being exposed to the action of heat, will also be irradiated with the ultraviolet rays emitted by the lamp filament. Experience has shown that the application of heat during ten to twenty minutes, more 45 especially if combined with the action of ultraviolet rays, exerts a favorable influence upon the inflamed parts and more especially on the mucous membranes.

In the modification illustrated in Fig. 2, 50 the lamps 10 are mounted in sockets 11 secured to the outer ends of a weak coil spring 12 held in a sleeve 13 which is mounted on a small handle 41 and through which extend the current conductors 14. If the lamps and 55 sockets are forced into the position shown

in dash lines by bending the coil spring 12, and the lamps are then inserted in the nostrils, the device will be held in position by the elastic pressure exerted by the spring and lamps on the outer walls of the nostrils. 60

The device shown in Fig. 3 consists of lamps 15 mounted in sockets 16, each of which is secured to one arm of a double-armed lever 18, the levers being hinged together at 19 and their outer arms being 65 acted upon by a pressure spring 20. If this device, which is here represented in exaggerated size, is placed in position, the lamps 15 being inserted in the nostrils, the upper portions of the sockets will be 70 forced by the pressure spring 20 against the part of the nose intermediate the nostrils, which will thus be clamped between the sockets, thereby holding the device in position. 75

In the modification shown in Fig. 4 the sockets 23 provided with leading-in conductors 25 and carrying lamps 26 are mounted on pins 23 for rotation about the ends of a strap 21 carrying short pieces 22 of 80 rubber tubing. In the practical operation of this device the two lamps 26 are turned into a position at right angles to the strap 21 and are then inserted into the nostrils, whereupon the strap 21 is turned into the 85 position in which the rubber envelopes 22 are applied against the bridge of the nose, thereby holding the lamps in position in the nostrils.

I wish it to be understood that I do not 90 desire to be limited to the exact details of construction shown and described for obvious modification will occur to a person skilled in the art.

I claim:—

1. A nasal treatment implement comprising a handle, two sockets pivoted to said handle in juxtaposition, a low voltage heating resistance applicator in each socket and means for connecting said sockets to a 100 source of current.

2. A nasal treatment implement comprising a handle, two arms linked to said handle, two sockets mounted on said arms, a low voltage heating resistance applicator in each 105 socket and means for connecting said sockets to a source of current.

3. A nasal treatment implement comprising a handle, two sockets secured to said handle in juxtaposition, a low voltage heat- 110

ing resistance applicator in each socket and means for connecting said sockets to a source of current.

4. A nasal treatment device comprising a handle, a support connected thereto at one end and adjustable relative to the handle, and a resistance applicator for applying heat to the parts affected connected to the end of said support and adjustable relative to both the handle and support.

5. A nasal treatment device comprising a handle, a pair of arms having a common

adjustable connection to the handle, and an applicator unit adjustably connected to each of said arms.

6. A nasal treatment device comprising a handle, a pair of resistance applicators adjustably connected with the handle so as to be adjustable relative to the handle, said applicators being also adjustable relative to each other, and means for connecting said applicators to a source of current.

In testimony whereof I affix my signature.
FRANZ KAHL.
